VENDING MACHINE FOR PASTRY, SANDWICHES,
CANNED GOODS AND THE LIKE

Walter E. Moore, Bel-Nor, Mo., assignor to National Vendors, Inc., St. Louis, Mo., a corporation of Missouri

Filed Feb. 2, 1959, Ser. No. 54,409

Term of patent 14 years

(Cl. D52—3)

FIG. 1.

FIG. 2.

FIG. 3.

Fig. 1 is a top plan view of a vending machine for pastry, sandwiches, canned goods and the like showing my new design;

Fig. 2 is a front elevation of Fig. 1; and

Fig. 3 is a right side elevation of Fig. 2.

The undisclosed side of the vending machine is substantially the same in appearance as the side shown, and the rear is plain and unadorned.

I claim:

The ornamental design for a vending machine for pastry, sandwiches, canned goods and the like, substantially as shown and described.
